UNITED STATES PATENT OFFICE.

JOHN COYNE, OF ALLEGHENY, PENNSYLVANIA.

NAIL-PLATE.

SPECIFICATION forming part of Letters Patent No. 331,944, dated December 8, 1885.

Application filed September 24, 1885. Serial No. 177,987. (No model.)

To all whom it may concern:

Be it known that I, JOHN COYNE, residing at Allegheny, in the county of Allegheny and State of Pennsylvania, a citizen of the United States, have invented or discovered certain new and useful Improvements in Nail-Plates, of which improvements the following is a specification.

In the accompanying drawings, which make part of this specification, Figure 1 is a plan view of my improved double nail-plate. Fig. 2 is a transverse sectional view of the same. Fig. 3 is a sectional view of a single nail-plate. Figs. 4 and 5 are similar views of a modified form of the plate, applicable to the manufacture of railroad and other spikes.

The object of my invention is to provide a nail-plate of such form and construction that nail-blanks having two parallel and two converging sides may be cut therefrom without turning the plate, thereby avoiding the waste arising from butts or plate ends; and it is a further object of my invention to so construct the plate that the nail-blank when cut will present unoxidized surfaces to the gripping and heading dies.

Referring now to Fig. 3, the single nail-plate is made of a width slightly greater than the length of the nail to be produced. The sides of such plate along one edge, which, for convenience, I term the "head" edge, are made parallel, as shown at 2. This parallelism of the sides should extend inward sufficiently far to provide the amount of metal necessary for the formation of the head; but the sides of the remaining portion of the blank—*i. e.*, that portion designed to form the body of the nail—are inclined, converging toward each other, as shown at 3, Fig. 3. If chisel-pointed nails are desired, the sides are beveled off along the point edge, as shown at 4. The plate thus constructed is fed into an ordinary nail-machine, and the nail-blanks are cut off by a series of parallel cuts, and are then headed by suitable dies, being held during such heading operation by gripping-dies acting on that portion of the blank having parallel sides. These nail-plates are made of steel or Bessemer metal by means of suitable grooved rolls, and as the plates are thicker at one edge than the other,

and would therefore curve or bend in the direction of the thick edge in passing through the rolls, I prefer to roll the plates double, as shown in Figs. 1 and 2—*i. e.*, of a width sufficient to form two nail-blanks. In the double plates 1^a that portion intended for the formation of the heads is formed along the middle portion of the plate, the sides along such middle portion being made parallel, as shown at 5, and this parallel portion 5 is made sufficiently wide to provide the metal necessary for the formation of two heads. From this central parallel portion the sides 3 of the plates converge toward each other, toward the edges of the plates. This double plate, which is double the width of the single plates shown in Fig. 3, and therefore adapted for the formation of two nail-blanks, is cut along the center of the parallel portion 5, the line of cut being represented by dotted lines in Figs. 1 and 2, thus forming two single nail-plates, such as is shown in Fig. 3. These double nail-plates are not only more easily rolled than the single plates, but by making the middle portion of the plate thick, for the formation of the nail-heads, and then cutting the plates apart along such thick portion, clean-cut surfaces are presented to the heading-dies, thereby preventing the destruction of the dies by the scale formed on the rolled surfaces.

In heading nails the gripping-dies grasp the nail on its parallel sides, which in the ordinary nail-blank are covered with scale formed in the rolling operation; but as the nail-blanks are cut from my improved blank by a series of parallel cuts, the gripping-dies do not come in contact with the scaly surface, but with the parallel-cut surfaces, thereby preventing the rapid wear of the dies from contact with scales or oxidized surfaces.

Another characteristic of the nails produced in the manner above stated is that the parallel sides of the nail, which are principally relied on for holding the nail in wood, are rough, being the cut surfaces, in lieu of comparatively smooth rolled surfaces, as in the ordinary nail.

In the plate shown in Fig. 4, which is adapted for the formation of spikes having parallel sides for the greater portion of their length, the central portion, 5, is made considerably

wider, as shown, and in the plate shown in Fig. 5, adapted for the formation of railroad spikes, the plate is made thicker along its central portion, 5, thus providing an increased 5 quantity of metal for the formation of the large heads employed in such spikes. This form of blank — *i. e.*, that shown in Fig. 5 — is also applicable to the manufacture of horseshoe-nails.

10 I claim herein as my invention—

1. A nail-plate having its side faces parallel to each other through so much or such part of the width of the plate as is necessary for the formation of the nail-head by a subsequent upsetting action, and having its sides 15 inclined toward each other from the parallel-sided portion to the edge of the plate, substantially as set forth.

2. A nail-plate having its middle portion, 5, formed with parallel sides, the remaining 20 portion 3 of said sides inclining toward each other from said middle portion to the edges of the plate, substantially as set forth.

3. A nail-plate having its middle portion formed with parallel sides 3, and ribbed, as 25 described, the sides of the plate on each side of the middle being made tapering to the edges of the plate, substantially as set forth.

In testimony whereof I have hereunto set my hand.

JOHN COYNE.
